UNITED STATES PATENT OFFICE.

RICHARD MANLY PELHAM AND CHARLES A. KUENZEL, JR., OF DENVER, COLORADO.

VAPOR-MIXER FOR AN INTERNAL-COMBUSTION ENGINE.

1,218,309.

Specification of Letters Patent.

Patented Mar. 6, 1917.

Application filed May 31, 1916. Serial No. 100,927.

To all whom it may concern:

Be it known that we, RICHARD MANLY PELHAM and CHARLES A. KUENZEL, Jr., both citizens of the United States, residing at Denver, in the county of Denver, State of Colorado, have invented a new and useful Vapor-Mixer for an Internal-Combustion Engine, of which the following is a specification.

10 Our invention consists of a device adapted to mix vapor for an internal combustion engine, the same comprising a casing adapted to contain water or other suitable liquid, a suction pipe leading from the 15 engine, an air supply member in communication with the atmosphere, and a vapor conductor leading from the radiator of the engine, so that the vapor will condense and join the water in the casing, said conductor 20 member and suction pipe entering said casing, whereby when the engine is in operation the free air from the atmosphere will be filtered or passed through water, and the vapor therefrom joins the gasoline, the mixture being directed to the engine, producing 25 superior results in that the power of the engine will be increased, gasoline will be saved, carbon trouble will be eliminated, and other advantages exist as will be hereinafter set forth.

The invention is satisfactorily illustrated in the accompanying drawing, but the important instrumentalities thereof may be varied, as long as they are included in the 35 scope of the claims.

Figure 1 represents a partial side elevation and partial vertical section of a device embodying our invention.

Figs. 2, 3, and 4 represent similar views 40 of other embodiments of the invention.

Similar numerals of reference indicate corresponding parts in the figures.

Referring to the drawings.

1 designates a cylinder or casing adapted 45 to receive a suitable supply of water, or other suitable fluid, and having connected at its top with the pipe 2 which leads to the carbureter of an explosive engine and opens into said casing as at 3.

50 Connected also with said top is the pipe 4 which extends from the overflow of the radiator 5 employed, and being connected therewith as at 6.

55 The end of the pipe 4 at the top of the casing has connected with it the pipe 7 which depends therefrom into said casing

and has its lower end open so as to be in communication with the interior of the casing as at 8 through the water into which said end dips.

60 Connected with the side of the casing are the tubes 9 which enter the casing and communicate with the same as at 10, said tubes being also in communication with the atmosphere as at 11, and likewise serving to supply the casing with water.

It will be seen that the suction from the engine in the pipe 2 will create a vacuum in the cylinder 1, and consequently in the pipes 7 and 4 which in turn sucks free air through 70 the tubes 11 so that the air filters upwardly through the water in the casing and is drawn into the casing. The vacuum in the pipes 7 and 4 also sucks the vapor in the radiator 5 from the same into the casing, 75 said vapor being condensed in the water in the latter, it being seen that owing to the suction of the pipe 2, the moist vapor in the cylinder rising from the water therein is directed to the gasoline producing in the 80 engine a highly effective gas, it being seen also that gasoline is saved, carbon trouble obviated, and the power of the engine increased.

In Fig. 2, we show a jacket 12 around the 85 lower portion of the casing 1, the latter having an open bottom, whereby it is in communication with the interior of the casing as at 13, said jacket having therein the ports 14 for the admission of air to the jacket, the 90 air filtering through the water in the jacket and casing, and so entering the latter, said ports also serving to supply the casing with water.

In Fig. 3, we show the pipes 15 which by 95 the branch 16 is connected with the bottom of the casing and in communication with the interior of the casing, said pipes being open to the atmosphere as at 17.

In Fig. 4 we show pipes 18 which are 100 connected with the side of the casing and enter the latter where they are coupled with the pipe 19 which dips into the water in the casing and has therein a port 20 which allows the water to enter said pipe 19, and 105 also allows the air directed into the latter by the pipes 18 at 21 to enter the casing and filter upwardly through the same as in the previous instances.

110 It will be noticed that as the vapor of the radiator enters the casing and condenses in the water in the latter it adds to the

volume of the water. Should there be any excess of water, it may overflow through the air receiving members without closing the latter to the atmosphere.

5 Having thus described our invention what we claim as new and desire to secure by Letters Patent, is:—

1. A vapor mixer for an internal combustion engine embodying a casing adapted to contain water or other suitable liquid, a suction pipe connectible with the engine, a suction pipe connectible with a radiator adapted to enter said casing, and a member for supplying atmospheric air to the interior 10 of said casing, the last-named suction pipe and said member communicating with said casing with their discharge openings below the surface of the liquid therein.
- 15 2. A vapor mixer for an internal com-

bustion engine embodying a casing adapted to contain water or other suitable liquid, a suction pipe connectible with an engine and with said casing, a member communicating with the atmosphere and connected with the casing with its discharge opening below the 25 surface of the liquid therein, and a suction pipe connectible with a radiator and entering said casing with its discharge opening below the surface of the liquid therein.

RICHARD MANLY PELHAM.
